UNITED STATES PATENT OFFICE.

VAHAN HAGOPIAN, OF NEW YORK, N. Y., ASSIGNOR TO AMERICAN ENAMELED BRICK & TILE CO., OF NEW YORK, N. Y., A CORPORATION OF NEW YORK.

DESIGN FOR A FLUTED COLUMN.

Application filed April 13, 1928. Serial No. 26,318. Term of patent 14 years.

To all whom it may concern:

Be it known that I, VAHAN HAGOPIAN, a citizen of United States, and resident of New York, in the county of New York and State of New York, have invented a new, original, and ornamental Design for a Fluted Column, of which the following is a specification, reference being had to the accompanying drawing, forming part thereof.

Figure 1 is a side elevation of a fluted column of my new design, and

Figure 2 is a diagrammatic representation of the cross sectional outline of the column.

I claim:

The ornamental design for a fluted column, as shown.

VAHAN HAGOPIAN.
